UNITED STATES PATENT OFFICE.

JOSEPH M. BOSENBURY, OF PEORIA, ILLINOIS, ASSIGNOR OF ONE-HALF TO CHARLES O. BIRNEY, OF MOUNT HEALTHY, OHIO.

AUTOMATICALLY-OPERATED CIRCUIT-BREAKER.

1,228,395.

Specification of Letters Patent. Patented June 5, 1917.

Application filed July 12, 1915. Serial No. 39,296.

To all whom it may concern:

Be it known that I, JOSEPH M. BOSENBURY, a citizen of the United States, residing at Peoria, in the county of Peoria and State of Illinois, have invented new and useful Improvements in Automatically-Operated Circuit-Breakers, of which the following is a specification.

This invention relates to apparatus for controlling electrically propelled vehicles or trains, and more particularly where a fluid pressure braking system is employed.

Various devices have heretofore been proposed for effecting an application of the brakes and automatically opening the motor circuit whenever the controller handle is released by the motorman in any of its operating positions.

The principal object of my invention is to provide an improved device of the above character and in which the motor circuit is opened before the brakes are applied.

In the accompanying drawing; Figure 1 is a diagrammatic view, partly in section, of a control apparatus embodying my invention; Fig. 2 a sectional view of the controller handle mechanism, showing the handle in position with the operator's hand removed; Fig. 3 a similar view, showing the controller handle locked in the "off" position; and Fig. 4 a plan view of the controller.

My invention is shown in the drawing as applied in connection with a pilot valve 1 which is adapted when opened to vent fluid under pressure from a pipe 2 which leads to an emergency valve device adapted to effect an application of the brakes when the pressure in the pipe 2 is reduced, a construction of this character being shown and described in a prior Patent No. 1,145,045 of W. V. Turner, dated July 6, 1915.

The pipe 2 opens into valve chamber 3, and in the present instance, instead of venting fluid directly to the atmosphere, the pilot valve 1, when opened, vents fluid to a pipe 4 which leads to piston chamber 5 in a casting 6 and containing a piston 7. The piston 7 is normally maintained in its inoperative position by a spring 8 and carries a stem 9 adapted to engage the lever 10 of a motor circuit breaker 11.

For operating the pilot valve 1, a lever 12 is pivoted to a bracket 13 secured to the

controller 14 and said lever is provided with a finger 15 adapted to engage the stem of 55 the pilot valve 1.

The controller handle 16 is pivoted for vertical movement on a handle bracket 17 secured to the controller shaft 18 and has a rearwardly extending forked arm 19 adapted to engage trunnions carried by a vertically movable rod 20.

The lower end of the rod 20 is adapted to engage the upper surface of the lever 12 and a spring 21 acts on the rod with a tendency 65 to force the same downwardly.

In operation, so long as the operator holds the controller handle down in the position shown in Fig. 1 of the drawing, the operation will be the same as that of the usual 70 controller. If the operator releases the handle in any of its operating positions, however, the spring 21 will immediately act to shift the rod 20 to the position shown in Fig. 2 of the drawing, thereby depressing 75 the lever 12 so as to cause the finger 15 to open the pilot valve 1. Fluid under pressure is then vented from pipe 2 to pipe 4 and the piston 7 is operated to throw the switch lever 10 so as to open the motor circuit. 80

When the piston 7 has moved out beyond the exhaust port 22, fluid will be vented from pipe 4 and consequently from the pipe 2 so that the emergency valve device will be operated by the reduction in fluid pressure to 85 effect an application of the brakes.

The lever 12 is prevented from operating in "off" position by providing a lug 23 on the lever 12 which extends up and around another lug 24 carried by the handle bracket 90 17, so that when the handle is moved to "off" position, with the handle depressed, the lug 24 will pass under the lug 23 and thus prevent the spring 21 from forcing the rod 20 downward, as shown in Fig. 3. 95

The handle 16 may be interlocked, to prevent movement from "off" position until the handle is depressed, by providing a hole 25 in the lever 12, into which the end of the rod 20 is adapted to drop when the controller 100 handle is moved to "off" position and the handle is released. By this means, the handle is locked in "off" position, from which it cannot be moved without first depressing the handle. 105

Having now described my invention, what

I claim as new and desire to secure by Letters Patent, is:

1. The combination with a controller handle, of a motor circuit breaker and means operated by fluid under pressure upon release of the controller handle for first effecting the movement of the circuit breaker to open the motor circuit and for then venting fluid to effect an application of the brakes.
  - 10 2. The combination with a controller handle, of a motor circuit breaker, a pipe a reduction in fluid pressure in which operates to effect an application of the brakes, valve means operated upon release of the controller handle by the operator for venting fluid from said pipe, and a piston device operated by fluid vented from said pipe for first effecting the movement of the circuit breaker to open the motor circuit and then
  - 15 20 adapted to open a vent port from said pipe to effect a reduction in pressure therein and thereby produce an application of the brakes.
  - 25 3. The combination with a controller handle, of a switch for controlling the motor circuit, a pipe normally charged with fluid under pressure, a reduction in pressure in which operates to effect an application of the brakes, a piston operated by fluid pressure for first effecting the movement of said switch to open the motor circuit and for then opening an atmospheric vent port to permit the escape of fluid under pressure, and a pilot valve operated upon the release of the controller handle by the operator for open-
  - 30 35
  - ing communication for admitting fluid from said pipe to said piston.
  4. The combination with a controller handle, of a vent valve, a lever operated upon release of the controller handle by the operator for actuating said valve, and a locking device for preventing movement of the lever when the controller handle is in "off" position.
  - 45 5. The combination with a controller handle, of a vent valve, a lever operated upon release of the controller handle by the operator for actuating said valve, a lug carried by the lever, a lug movable with said handle and adapted to interlock with the lug on the lever in the "off" position of the handle to prevent movement of the lever when the handle is released by the operator.
  - 50 6. The combination with a controller handle, of a pilot valve, a lever for operating said valve, a spring, and a rod operated by said spring upon release of the controller handle by the operator for actuating said lever, and adapted to engage in a recess in the lever when the controller handle is in "off" position, to prevent movement of the handle from said position unless the handle is depressed.
  - 55 60
- In testimony whereof I have hereunto set my hand.
- JOSEPH M. BOSENBURY.
